ELECTRIC HEATING ELEMENT.

1,081,414.

Specification of Letters Patent.

Patented Dec. 16, 1913.

Application filed May 6, 1913. Serial No. 765,816.

To all whom it may concern:

Be it known that I, ALONZO A. WARNER, a citizen of the United States, and a resident of New Britain, in the county of Hartford and State of Connecticut, have invented certain new and useful Improvements in Electric Heating Elements, of which the following is a specification.

The structure of this invention is intended for use in electrically heated utensils of various sorts, such as are found in general use today.

The object of the invention has been to provide a heater which would produce a maximum of heating effect in a minimum of space, which means that there must be a maximum amount of resistance material in a minimum space. In addition it has been my purpose to make this heater pliable in order that it may be installed in a variety of ways and to suit any peculiar requirements of a given case.

Other features and advantages of the invention will become apparent from a consideration of the following description and claims.

I have illustrated one embodiment of my invention in the drawings, where—

Figure 1 is a side view of a section of a heater made in accordance with my invention, and Fig. 2 is an end view thereof.

By reference to the drawings it will be seen that my new heater consists of a compound coil of wire of the kind which when heated becomes coated with an insulating oxid, the primary or minor coil preferably being closely coiled so that its convolutions are in contact; this primary coil is then wound preferably under slight tension about a small temporary arbor into a very compact secondary or major coil, the adjacent convolutions of this major coil being out of contact, and the convolutions of the minor coil being spaced on the outer circumference of the major convolutions, while they may be in contact about the inner circumference of the major convolutions, as clearly seen in Fig. 2. This heater is wholly unsupported except through the stiffness or rigidity of the material from which it is made; free circulation of air through the heater is provided for, which means that

radiation of the heat takes place from all parts of the heater, thus making it possible to utilize to the fullest degree all heat which is evolved. Since the heater is not formed upon a core it is pliable and can be shaped to suit the requirements of various installations.

I am aware that heretofore it has been proposed to wind a coil of resistance wire about a core of insulating material, and I desire to here point out that my invention is distinguished from such a construction in that it is a self-supporting structure, the entire surface of which is subject to effective radiation of the heat evolved, and is pliable in order that it may be shaped to fit the recess within which it is to be installed.

It is obvious that the size of the wire used is to be varied to suit the different conditions, and that the shape of the convolutions of the minor coil can be varied. For instance, after the minor coil has been formed it may be flattened so as to reduce the total length of the completed element but slightly increasing its diameter. The broader aspect of the invention, namely, a self-supporting pliable heater providing a maximum of heating effect within a minimum space, may be present in a structure wherein the primary member is not in the form of a coil but takes another shape, such as a crimped wire which may then be wound to form a major coil.

I claim as my invention:—

1. An electrical heating element in the form of a self-supporting pliable coil formed from a suitable resistance wire, the length of the wire in each convolution being greater than the circumference of the convolution.

2. An electrical heating element in the form of a self-supporting pliable compound coil, the convolutions of the major coil being out of contact.

3. An electrical heating element in the form of a self-supporting pliable compound coil, the adjacent convolutions of the minor coil having points of contact with one another, and those of the major coil being out of contact.

4. The herein described method of forming an electrical heating element which con-

sists, first in forming a strand of resistance material into a closed coil with its convolutions in contact, and second in winding this coil about a temporary mandrel into a second coil whose convolutions are out of contact, the first coil being subjected to a slight tension while being wound into the second

coil in order to open up the outer parts of its convolutions.

ALONZO A. WARNER.
